CONTAINER OPENER

Cornelius Gaasbeck, Brooklyn, N. Y.

Application May 18, 1950, Serial No. 162,710

7 Claims. (Cl. 30—16)

1

This invention relates to container openers, and the main object is the provision of a useful, practical and simple implement having means for puncturing the tops of tin cans, means for lifting the lids off bottles, jars, and the like, and further having adjustable means whereby the implement may be readily adapted to accommodate the size of the container or cap to be worked upon.

Another object of the invention is to provide a container opener so constructed as to permit of removal of a bottle cap, jar lid or the like without damage to the cap or lid so that the same may be reapplied as a closure.

The above broad as well as additional and more specific objects will be clarified in the following description, wherein characters of reference refer to like-numbered parts in the accompanying drawing. It is to be understood that the drawing is intended solely for the purpose of illustration, and that it is therefore neither desired nor intended to limit the invention necessarily to any or all of the exact details of construction except insofar as they may be deemed essential to the invention.

Referring briefly to the drawing, Fig. 1 is a perspective view of a container opener embodying the useful features of this invention.

Fig. 2 is a sectional view taken on the line 2—2 of Fig. 1.

Fig. 3 is a perspective view of the slidably adjustable gripping tongue of the implement, per se.

Fig. 4 is a sectional view taken on the line 4—4 of Fig. 2.

Fig. 5 is a fragmentary elevational view of a tin can, with parts broken away and partly in section, showing also in side elevation the tool of this invention applied thereto in the operation of puncturing the top of the can.

Fig. 6 is a fragmentary elevational view of a bottle, showing the tool in side elevation applied thereto in the operation of removing the bottle cap.

Fig. 7 is a fragmentary elevational view of a jar, showing the tool in side elevation applied thereto in the operation of removing the lid.

Referring in detail to the drawing, the numeral 10 indicates the tool or implement of this invention, which comprises an elongated flat body 11 having an opening 12 on one end whereby it may be hung from a hook or the like. The other end 13 of the body 11 is deformed to extend generally downward therefrom at an angle thereto. The deformed end 13 tapers to a nose 14. The base 15 of the end 13 extends at approximately 45 de-

2

gress to the body 11, and the intermediate portion 16 of the end 13 lies at an angle of approximately 120 degrees to the base 15, and the nose 14 at an angle of approximately 60 degrees to the body 11. As a result, the nose 14 is turned downward, with respect to the body 11, at a greater angle than the base 15 of the end 13. The bight 17 between the base 15 and the intermediate section 16 of the end 13, is rounded, at least to a small degree.

A central longitudinal slot 18 extends part way of the length of the body 11 from a point near the base of the end 13. A carriage 19 comprises a flat plate 20 whose width is greater than that of the slot 18 and which may be equal to that of the body 11. A rectangular block 21 whose width is very slightly less than the width of the slot 18 so that it may register in the said slot, is formed integrally with the upper surface of the plate 20. A screw 22 passes upward through a hole 23 in the plate 20 and an aligned hole 24 through the block 21 and projects a distance above the latter. The carriage 19 is slidably mounted on the body 11 by registering the block 21 in the slot 18. A wing nut 25 engages the screw 22 to clamp the carriage 19 to the body 11 at any position along the slot 18, and a washer 26 is preferably interposed under the nut 25.

The forward end 27 of the plate 20 is deformed substantially as shown to provide a grip 28 positioned below the plane of the plate 20 and approximately parallel therewith.

In use, the carriage 19 is first positioned along the slot 18 to accommodate the device to the size of container to be opened, in an obvious manner. When applied to puncture the top of a can, as shown in Fig. 5, the grip 28 is engaged under the bead 29 of the can, whence a forceful anti-clockwise rotation of the implement about the edge of the grip 28 causes the nose 14 to puncture the can.

When used to remove a bottle cap, as shown in Fig. 6, the grip 28 is engaged under the overhang of the cap 30. It is to be noted that the bight between the body 11 and the base 15 of the end 13 is well rounded, as shown at 31. The carriage 19 is here so positioned that the rounded bight 31 engages the rim of the cap 30, so that on swinging the implement in a counter-clockwise direction the forward end of the body 11 serves to support a substantial portion of the cap surface including that under the bight 31. Thus, the cap is removed by the implement without damaging it so that it may be reapplied to the bottle as a seal.

In removing the lid 32 of a jar 33, as shown in

3

Fig. 7, the grip 28 is again engaged under the overhang of the lid, with the carriage 19 so positioned on the body 11 that the section 16 engages the opposite edge of the rim of the lid. Thus, here also the engagement of the rim at the point opposite the grip 28 controls the lid so that when the counter-clockwise movement of the implement removes the lid the latter remains undamaged so that it may again be applied as a seal on the jar.

Obviously, modifications in form or structure may be made without departing from the spirit or scope of the invention.

I claim:

1. An implement of the class described comprising an elongated flat body having the forward end thereof deformed and extending downward at an angle to the plane of the body, said deformed end tapering toward its extremity thereby providing a nose at the extremity of said deformed end, said body having a longitudinal slot therethrough extending partway of the length of the body from a point rearward of said deformed end, a carriage slidably mounted on said body and having a block thereon registering slidably in said slot, releasable means for locking said block and hence said carriage at any longitudinal position within the range of said slot, said carriage having an extension thereon extending downward from the plane of said body, said extension having the extremity thereof extending forward approximately parallel with said plane.

2. The implement set forth in claim 1, said deformed end of said body being rounded at the juncture thereof with said body.

3. The implement set forth in claim 1, said deformed end of said body being rounded at the juncture thereof with said body, said deformed end comprising in addition to said nose a base section and an intermediate section, said base section extending at approximately an angle of 45 degrees to said plane of the body, said intermediate section extending at approximately an

4

angle of 120 degrees to said base section, and said nose extending at an angle of approximately 60 degrees to said plane of the body.

4. The implement set forth in claim 1, said means comprising a screw extending from said block through said slot and a nut on said screw to clamp said body between said carriage and said nut.

5. The implement set forth in claim 1, said means comprising a screw extending from said block through said slot upward from and at right angles to said plane, a washer having a diameter greater than the width of said slot positioned on said screw above said plane, and a nut on said screw above said washer to clamp said body between said carriage and said nut.

6. A container opener comprising an elongated flat body having the forward end thereof deformed and extending downward at an angle to the plane of the body, said body having a longitudinal slot therethrough extending partway of the length of the body from a point rearward of said deformed end, a carriage slidably mounted on said body, said carriage comprising a block registering slidably in said slot, a plate secured to the lower end of said block and having its upper surface in slidable contact with the lower surface of said body, said plate having a width greater than the width of said slot and having an extension thereon extending downward from the plane thereof, said plate extension having the extremity thereof extending forward approximately parallel with the plane of said body, said carriage having means for locking the same on said body at any longitudinal position within the range of said slot.

7. The device set forth in claim 6, said means comprising a screw extending upward from said block, and a nut on said screw to clamp said body between said plate and said nut.

CORNELIUS GAASBECK.
